ABSTRACT

Apparatus for marking spherical articles in which the marking means extends upwardly from beneath and a concave transparent template having a design scribed therein is held above the article. The article is provided with a follower so that when the article is rotated beneath the template, the follower will track and the marking means will function on the bottom of the spherical article.

AXIS OF ROTATION

SHEET 1 OF 2

FIG. 2.## APPARATUS FOR MARKING SPHERICAL ARTICLES

The present invention relates to marking apparatus for marking spherical articles, such as bowling balls, with a design, typically the name of the owner. The marking means which is particularly contemplated is a rotatable bit which scribes the desired design into the surface of the spherical article.

This invention thus has the same objective as my prior U.S. Pat. No. 3,179,013 dated Apr. 20, 1965.

In my said prior patent, the rotatable bit presses against the upper surface of the bowling ball, as pictured in FIG. 1 of the patent, and there is little opportunity to employ a template to guide the rotation of the ball so as to aid the application of the desired design.

In this invention, the spherical article is supported for rotary movement in all directions (as taught in my prior patent or using simplified support means shown herein) and the support element is annular so that the marking means can be positioned beneath the support to extend upwardly through the annular opening to bear against the spherical article when the same is supported. A stationary template support means extends above the support element to hold a template slightly above the upper surface of the spherical article. The template is concave and removable and its concave undersurface has a design inscribed therein. In this way, a follower carried by the spherical article will track through the design forcing the rotation of the article to move the undersurface of the article against the marking means. This causes the undersurface to be marked with a copy of the design on the template.

As will be evident, the template can be made by one expert in scribing designs, and anyone can follow it. Also, if an error is made, it is made on an inexpensive template, and not in the expensive bowling ball.

The invention will be more fully understood from the accompanying drawings in which:

FIG. 1 is a side elevation, partly in section showing an illustrative device constructed in accordance with the invention; and

FIG. 2 is a top plan view of the structure shown in FIG. 1.

Referring more particularly to the drawings, FIG. 1 shows the structure in operation scribing a design into the undersurface of a bowling ball. The marking means 10 comprises an elevated work table 11 which is supported by legs shown at 12 and 13. An annular ball race 14 is shown supported at the center of the table 11, the table 11 having a hole 15 formed therein underlying the race 14 so that a drill press or router 16 which is carried beneath the table 11 can push its cutting bit 17 upwardly through the hole 15 and then through the annular opening in the race 14. The bit 17 is supported by a chuck 18 and the elevation is controlled by the conventional control mechanism, here indicated diagrammatically by the control mechanism 20. The drill press

or router 16 is secured by screws 19 to the table 11 so as to be stably positioned beneath hole 15.

The bowling ball 21 rests on the race 14 as pictured, and the ball is free, except for a template and a spider support therefor to be described, so that the ball 21 can be rotated as desired by mere hand pressure applied to the ball.

A pair of template support arms 22 and 23 are secured to work table 11 by screws 24 and a template 25 is secured thereto above the ball, as by screws 26. The template is concave as shown, and its undersurface has design 27 inscribed therein.

As can be seen, a follower 28 (a pin or peg which can be spring loaded) is secured to the surface of the ball 21 and this pin is guided into the design 27. The follower can be mounted in a hole in the ball or it can be taped to the ball. At this point, the drill press or router 16 is started and control 20 is advanced to start the scribing action, whereupon the ball 21 is hand rotated to move the follower 28 through the track of the design. The template 25 is made of transparent plastic to aid this effort. When finished, the drill press or router is turned off, and the bit 17 is lowered.

The nature of the spider arms 22 and 23 of the template will be more easily seen from FIG. 2, and these can be changed to accommodate balls of different size.

The invention is defined in the claims which follow.

I claim:

1. Marking apparatus for a spherical article comprising, an annular support element for rotatably supporting said spherical article for rotary movement about the center of the spherical article in all directions, marking means extending upwardly from beneath said support element and extending through the annular opening thereof to bear against said spherical article when said spherical article is supported by said support element, stationary template support means extending above said support element for holding a template adjacent the upper surface of a spherical article supported by said support element, and a concave template removably carried by said template support means, the concave undersurface of said template having a design inscribed therein and a follower means carried by said spherical article to track through the design in the template when the spherical article is rotated to concurrently move the undersurface of the spherical article against said marking means to cause the same to mark the undersurface of the spherical article with a copy of the design on said template.

2. Apparatus as recited in claim 1 in which said template is transparent.

3. Apparatus as recited in claim 1 in which said marking means is a rotatable bit for scribing the desired design into the spherical article which is a bowling ball.
